(57) **CLAIM**

The ornamental design for an apparatus hanger, as shown and described.

DESCRIPTION

FIG. 1 is a perspective view of the new design;
FIG. 2 is a top view of the new design;
FIG. 3 is a bottom view of the new design; and,
FIG. 4 is a left side view of the new design the right side
being a mirror image of the left side.

The broken lines are included for illustrating the contours of
the design and have the same meaning as the longer length
contour lines.
